UNITED STATES PATENT OFFICE

2,169,572

CIGARETTE DISPENSER

Mario Tanzi, Chicago, Ill.

Application August 4, 1938, Serial No. 223,105

3 Claims. (Cl. 206—41)

The object of the invention is the provision of a dispenser which may be easily opened, which will remain open and which may be automatically returned to normal closed position by the action of resilient means, responsive to a slight change in pressure on the sides of the box.

One of the features of the invention resides in the arrangement of the inner sliding box within the outer box or case so that when the sides of the outer box are moved outwardly by the pressure of the resilient means as elastic bands, thereon, the edges of the outer box are brought into firm engagement with the edges of the inner box so that the dispenser is retained in its open position after being moved, thereto.

Another feature, closely related to the one just noted, resides in the arrangement and proportions of the inner and outer boxes and the retractile elastic band whereby, if the dispenser is open, a slight pressure on the opposite sides of the outer box will cause the edges of the outer box to move from braking engagement with the edges of the inner box, whereupon the elastic bands will cause the inner box to quickly return to its normal closed position within the outer box or casing.

Another feature, which results from a modification of the arrangement above described, resides in the proportions of the inner box in relation to the outer box or casing, whereby the inner box is not held in open position due to the distortion of the sides of the outer box by the elastic bands but may be retained in open position by a slight pressure on the lateral faces or edges of the outer box, adjacent to the end, thereof, from which the inner box is adapted to project. Substantially the same operation may be obtained by making the sides of the outer casing of stiffer material so that they will not be bulged outwardly to any material extent by the pressure of elastic bands thereon. In either form of the invention, the inner box may be returned to its closed or normal position by a slight change of pressure on the opposite sides of the outer casing,—in one case, by a slight increase in pressure and in the other, by a slight decrease in pressure.

Other features, advantages and modifications will appear from a detailed description of the invention taken in connection with the accompanying drawings, in which

Fig. 1 is a view of the dispenser in open position;

Fig. 2 is a view of device at right angles to that of Fig. 1;

Fig. 3 is a transverse section on the line B—B of Fig. 1;

Fig. 4 is a longitudinal section on the line A—A of Fig. 2;

Fig. 5 is a view of looking at the top of Fig. 1, part being broken away;

Fig. 6 is a view substantially on the line C—C of Fig. 2 looking in the direction of the arrows, but on a larger scale;

Fig. 7 is a view similar to Fig. 1, but showing a modification in which but one hinged section is provided at the end of the inner box;

Fig. 8 is a view similar to Fig. 1, but shows the lateral edges of the inner box hinged;

Fig. 9 shows an arrangement similar to that of Fig. 7, but with a hinged section at one lateral edge instead of at the side;

Fig. 10 is a side view of the box in normal or closed position, and

Fig. 11 is an end view of the box as shown in Fig. 10.

Reference will now be made to the drawings in which like reference characters indicate the same parts in several views.

Referring first to Figs. 1 to 6, inclusive, 1 indicates the outer box or casing which is rectangular in cross-section. The casing 1 has one edge rebent as shown at 2 to provide a stop or abutment which acts to limit the movement of the inner box 3 within the casing 1. The inner box 3, in cross-section, has substantially the same form and proportions as the casing 1 and is of a size such that it fits snugly within the casing 1 but is free to slide therein. The inner box 3, at the end, thereof, adapted to project from the casing 1, is divided centrally for approximately $\frac{1}{3}$ of its length to provide the hinged portions 4 which are joined to the sides 5 of the inner box as indicated at 6. This may be accomplished by merely bending or breaking the material along the line of the hinge so as to render it flexible, or the hinge may be provided in any other desired manner as by the use of flexible paper or fabric. Each of the hinged portions 4, has at its outer end thereof, a portion 7 extending inwardly at right-angles thereto. When the box is in closed position, the laterally extending portions unite to form the end closure for the inner box, as seen in Fig. 11. The lateral edges of the inner box may be cut away, if desired, throughout the extent of the portions 4 as indicated in the drawings.

Each of the hinged portions 4 is joined to the outer casing 1 through the medium of a strip of elastic material in the following manner: A rub-

ber band 8 has one end 9 secured to a side of the outer casing, at a distance from the end, thereof, from which the inner box projects, in any desired manner. In the present embodiment of the invention, a staple 10 has been employed for this purpose, as illustrated in Fig. 6. The other end 11 of each elastic band 8 is joined to a hinged portion 4, adjacent to the laterally extending part 7. This may be accomplished by extending the end 11 of the band through part 4, a piece 12 of wire or other firm material being received by the bight of the band to distribute the pressure exerted thereby. The wire 12 will preferably be secured in the corner between parts 4 and 7 by glueing paper thereover, or in any other desired manner. The band 8 is so arranged as to be under slight tension when the inner box 3 is nested in its normal position within the casing 1.

The operation of the form of the device just described is as follows: When it is desired to dispense the cigarettes or other objects within the box, the inner box 3 is pushed out of the casing 1, as by the finger of the operator applied to the solid closed end of the inner box. When the inner box 1 has been moved outwardly to about the position shown in Fig. 1 of the drawings, the elastic bands 8 will have acted to move the hinged portions 4 to open position as clearly shown in Figs. 1 and 4. The pressure of the elastic bands 30 on the sides of the outer box or casing will now cause the edges of the casing to be bulged outwardly as shown in somewhat exaggerated manner in Fig. 3 of the drawings. The bulging of the sides of the casing outwardly causes the edges of 35 the casing firmly to engage the edges of the inner box so as to exert a braking action, thereon, and retain the inner box in its outer or open position. When it is desired to close the box, a slight pressure may be exerted on the bulged portions at 40 the opposite sides of the casing whereupon the edges of the casing will move outwardly to release the inner box which is then returned to normal closed position by bands 8. In returning to normal, the end of the inner box engages the abutment 45 2, formed at the end of the casing, and the inner box will nest exactly within the casing as shown in Fig. 10. When the box is in open position, the opposite sides 5 of the inner box 3 will be curved inwardly, as indicated in Fig. 3, due to 50 the stress exerted by bands 8. This has the effect of slightly gripping the cigarette package so that it will remain in the dispenser when removing cigarettes from a full package.

A somewhat different manner of operating the dispenser may be brought about if the sides of the casing 1 are made somewhat stiffer or the edges are spaced slightly farther apart. In such a structure, the pressure of the bands 8 outwardly on the sides of the casing will not act automatically to retain the box in open position. The box, however, may be retained in open position by a slight pressure on the opposite edges of the casing, adjacent to the end from which the inner box projects. This causes the edges of the casing 65 to engage the inner box and hold it open. When the pressure is released, the box returns to its normal closed position.

In Fig. 7 is shown a modification in which the inner box has but one hinged end section, designated as 4a. The hinged section 4a of Fig. 7 is similar to the section 4 of Fig. 1 and is hingedly supported in the same manner. The laterally extending portion 7a, however, is approximately twice the width of the similar part 7 in Fig. 1. 75 In the form shown in Fig. 7, the end of the inner

box 3 may be cut away down to the point where the part 4a is hingedly joined to the side of the inner box. This form of the device will operate in substantially the same manner as above described in connection with the form shown in Figs. 1 to 6, the laterally extending part 7a acting as the sole closure for the end of the box.

The hinged sections may be provided at the edges or narrower faces of the inner box as shown in Fig. 8, wherein the parts have been indicated by the same reference characters as the corresponding parts in Figs. 1 to 6, but with the suffix "b" added, thereto. This box will operate in exactly the same manner as described in connection with the box shown in Figs. 1 to 6.

Fig. 9 shows a device similar to that of Fig. 7, but with a single lateral face or edge hingedly supported. The parts in this figure are indicated by the same reference characters as the corresponding parts in Figs. 1 to 6, but with the suffix "c" added.

It will be obvious that applicant has provided a dispenser which may be caused to move from its open position to its normal or closed position without changing the position of the hand holding the dispenser, only a slight change in pressure on the opposite faces of the box being necessary to permit it to automatically close. In no case is it necessary to manually move the hinged portions in order to effect closure of the box.

While applicant has described different embodiments of the invention, it is obvious that many modifications may be made in the details of the structure without departing from the spirit of the invention. The invention should, therefore, be limited only by the scope of the appended claims.

In the following claims the expression "flexible means joining the hinged section to the box" is meant to cover any means defining a line of flexure, such as formed by creasing or grooving or otherwise thinning the material of the box at this line.

Having described my invention, what I claim is new and desire to secure by United States Letters Patent is:

1. In a dispenser case, an outer tubular casing, generally rectangular in cross-section, an inner box of substantially the same contour in cross-section as said outer casing, slideable into and from said casing, said inner box closely fitting within said outer casing, a hinged section at one end of said inner box, flexible means joining said hinged section to the corresponding side of the inner box, a laterally projecting extension at the outer edge of said hinged section so arranged that when the box is in normal position, it forms a closure for the end of the box, and an elastic band having one end joined to said hinged end section remote from its hinged connection to the side of said inner box, the other end of said band being joined to a side of the outer casing remote from the end thereof from which the inner box is adapted to project, the said elastic band being positioned between the said casing and said box the casing being so proportioned to the box that two opposite sides of the casing closely fit the box while the other two opposing sides loosely engage the box so that a side of the outer casing may be outwardly distorted by the elastic band as the inner box is thrust out; such distortion being modifiable by light finger pressure inward on the outer casing to vary the frictional engagement of the outer casing on the inner box to control

the tendency of the elastic band to return and close the box.

2. In a dispenser case, an outer tubular casing, generally rectangular in cross-section, an inner box of substantially the same contour in cross-section as said outer casing, slidable into and from said casing, said inner box closely fitting within said outer casing, a hinged section at one end of said inner box, flexible means joining said hinged section to the corresponding side of the inner box, a laterally projecting extension at the outer edge of said hinged section so arranged that when the box is in normal position, it forms a closure for the end of the box, and an elastic band having one end joined to said hinged end section remote from its hinged connection to the side of said inner box, the other end of said band being joined to a side of the outer casing remote from the end thereof from which the inner box is adapted to project, the said elastic band being positioned between the said casing and said box, characterized in this that the parts are so proportioned that two opposite sides of the casing closely fit the box while the other two sides of the casing loosely engage the box, so a side of the casing may be distorted outward by the elastic band as the inner box is thrust out; such distortion being reversible by a light finger pressure inward against the outer casing causing it to frictionally engage the inner box, to hold the box projected, but retractible by the elastic band upon relief of the pressure.

3. In a dispenser case, an outer tubular casing,

generally rectangular in cross-section, an inner box of substantially the same contour in cross-section as said outer casing, slidable into and from said casing, said inner box closely fitting within said outer casing, a hinged section at one end of said inner box, flexible means joining said hinged section to the corresponding side of the inner box, a laterally projecting extension at the outer edge of said hinged section so arranged that when the box is in normal position, it forms a closure for the end of the box, and an elastic band having one end joined to said hinged end section remote from its hinged connection to the side of said inner box, the other end of said band being joined to a side of the outer casing remote from the end thereof from which the inner box is adapted to project, the said elastic band being positioned between the said casing and said box, characterized in this that two opposite sides of the casing closely fit the box, the other two sides of the casing loosely engage the box, so that the outward pressure of the elastic band on the side of the outer box engaged thereby, causes said side to be distorted outwardly, whereby the lateral edges of said outer box, adjacent to said distorted side, are drawn toward each other into firm engagement with the corresponding sides of the inner box so as to retain the box in open position until inward pressure applied to the distorted side releases the inner box and permits the elastic band to retract and close it.

MARIO TANZI.
